UNITED STATES PATENT OFFICE.

MARIE MARGARET O. DILLMAN AND MARY LOUISE AUGER, OF SPOKANE, WASHINGTON.

WORK-HOLDER.

No. 866,195.

Specification of Letters Patent.

Patented Sept. 17, 1907.

Application filed May 8, 1907. Serial No. 372,545.

To all whom it may concern:

Be it known that we, MARIE MARGARET O. DILLMAN and MARY LOUISE AUGER, citizens of the United States, residing at Spokane, in the county of Spokane 5 and State of Washington, have invented a new and useful Work-Holder, of which the following is a specification.

This invention relates to work holders and is particularly designed for holding embroidery hoops and the 10 like.

The object of the invention is to provide a simple, durable and compact device of this character which is attractive in appearance and which can be readily carried within a satchel or work bag.

15 Another object is to provide a clamp capable of being readily attached to a table or chair and which can be adjusted annularly and in the direction of its length.

With these and other objects in view the invention 20 consists of certain novel features of construction and combinations of parts which will be hereinafter more fully described and pointed out in the claims.

In the accompanying drawing is shown the preferred form of the invention.

Said drawing is a perspective view of the clamp, a 25 portion thereof being broken away, the chair arm to which it is secured and the embroidery hoops held by the clamp being shown in dotted lines.

Referring to the drawing by characters of reference, 1 designates a shank having jaws 2 extending therefrom and one of these jaws is provided with a set screw 30 3 on which is swiveled a head 4. Shank 1 has a tubular extension 5 slidably and revolvably mounted thereon and the outer end of this extension is preferably solid and has a flat working face 6 at the inner end of 35 which is formed a supporting shoulder 7.

An arm 8 is formed with or secured to the extension 5 and has a jaw member 9 pivoted thereto and having a flattened face 10 designed to coöperate with the surface 6 for clamping upon an object placed within the 40 device. An adjusting screw 11 extends loosely

through the member 9 and is threaded to engage the extension 5. A spring 12 is interposed between extension 5 and the jaw member 9 and is designed to swing the member 9 away from the extension when the screw 11 is turned in one direction. A set screw 45 13 extends into the extension 5 and is designed to bind upon the shank 1 so as to prevent the extension from moving independently thereof.

In using the device herein described the same may be attached to a table or to the arm of a chair, as indicated at 14, by placing the jaws 2 at opposite sides of the object to be clamped and turning the screw 3 so as to bind upon said object. If embroidery hoops such as shown at 15 are to be supported by the clamp they are placed between the extension 5 and the jaw member 9 so as to rest on shoulder 7 after which the screw 11 is turned so as to cause the parts to bind upon the hoops. The device can then be adjusted by loosening the screw 13 whereupon the extension 5 can be moved longitudinally or rotated in order to bring the hoops 60 into a desired position.

What is claimed is:

A work holder comprising a shank, jaws integral therewith and extending therefrom, a clamping device carried by one of the jaws, a tubular extension slidably and revolvably mounted upon the shank, an arm extending from and surrounding the extension, means projecting through and engaging the extension and arm for securing the extension against movement upon the shank, said means also constituting a fastener for the arm, a jaw member pivotally 65 connected to the arm, the ends of said tubular extension 70 constituting a jaw disposed to coöperate with the jaw member, means for adjusting said jaw member toward the extension, and resilient spacing means interposed between the extension and jaw member.

In testimony that we claim the foregoing as our own, we have hereto affixed our signatures in the presence of two witnesses.

MARIE MARGARET O. DILLMAN.
MARY LOUISE AUGER.
